VENDING PACKET

James Wellford Martin, Yonkers, N. Y.

Refiled for abandoned application Serial No.
504,706, December 26, 1930. This application
April 27, 1937, Serial No. 139,155

7 Claims. (Cl. 312—91)

The present invention relates to vending packets and more particularly to sheet material vending packets and to a method of making the same.

It is an object of the invention to provide a vending packet which can be made from one continuous piece of sheet material in such a manner that it can be shipped in a flat knocked down condition to the point of use or filling where the sheet material can be folded in position to 5 form a packet with projecting shelves for supporting articles of merchandise.

It is another object of the invention to provide a vending packet which can be filled with articles of merchandise at a factory or distribution station and then shipped in a box to users who will only have to remove the packet as an entity and insert the same in a vending cabinet.

It is a further object of the invention to provide a unitary vending packet of cardboard which 10 is formed and cut in such a manner that when folded a multiplicity of superimposed units are made from one blank.

It is a further object of the invention to provide a vending packet constituted of sheet material and formed into a multiplicity of units with 15 projecting shelves which project from the back of the packet and which are constructed of two floors separated from each other by an air space.

It is a further object of the invention to provide a method of making vending packets of the type herein described which can cut and form the vending packets from one continuous strip 20 or sheet of cardboard or other sheet material.

Other objects and advantages will become apparent from the following description taken in conjunction with the accompanying drawings in which:

Fig. 1 is a somewhat fragmentary view of a preferred vending packet embodying the principle 25 of the present invention;

Fig. 2 is a view of a blank from which the vending packet is made;

Fig. 3 is a view similar to Fig. 1 of a modified embodiment of the present invention;

Fig. 4 is a view of a blank from which the vending packet shown in Fig. 3 is made;

Fig. 5 is a cross section view of a container such as a vending cabinet, in which an improved vending packet is mounted;

Fig. 6 is a fragmentary view showing a longitudinal section of the lower portion of the vending cabinet shown in Fig. 5.

Fig. 7 is a longitudinal sectional view, some- 50 what fragmentary, of a modified embodiment of

the invention, into a weight actuated vending cabinet.

Referring more particularly to Fig. 1 the reference character 23 designates the wall members or portions of my improved vending packet. Projecting from the wall 23 are a plurality of shelves 19. These shelves are constituted of an upper and lower floor 6 and 6a respectively which are separated by an air space 1. In the present instance, this air space has a triangular cross section due to the fact that the upper and lower floors are joined at the outermost edges in practically a straight line. Of course, the air space may be rectangular in cross section and the front edges of the upper and lower floors may be joined 10 or united with a piece of sheet material.

The shelves are held in their projecting position by the provision of a pair of bands 2 which are located at each side of the vending packet. In the present embodiment, the bands are formed 20 from and are integral with wall 23 and upper and lower floors 6 and 6a of shelves 19. These bands may or may not be glued to each other and to wall 23 by means of any suitable adhesive such as glue, paraffin, paste or the like at joints 10. 25 Instead of cementing the bands to each other and to wall 23, a strip of paper or tape can be affixed to the front face of the bands or to the front face of the bands and the marginal edge portion of the rear of wall 23. As one skilled in the art 30 will readily understand the use and construction of these binding strips or tapes, they have not been illustrated in the drawings.

The improved vending packet depicted in Fig. 1 can be made from a single sheet of material 35 such as cardboard. A portion of a blank from which the vending packet is made is shown in Fig. 2. It will be clearly observed that score lines 12 which extend across the entire width of the blank define the upper and lower boundaries of 40 each of the walls 23. Between score lines 12 a slit or cut 3 is provided which extends from the lower boundary of one wall to the upper boundary of an adjacent wall. Extending outwardly from edge of cut 3 is a score line or perforation 16. 45 This score line forms the strip of sheet material between the side of the blank and the cut and between adjacent score lines 12 into bands 2. Set back or staggered from score lines 16 is a score line 5 which forms the area between adjacent 50 cuts 3 and adjacent score lines 12 into the upper and lower floors of 6 and 6a. In this manner a strip of sheet material such as cardboard can be cut and formed into a blank from which the improved vending packet can be made. It is clear 55

that the present method provides a procedure for manufacturing vending packets embodying the principles of the present invention from a continuous strip of cardboard or other sheet material.

5 When the blank is formed into a vending packet sufficient material can be taken so as to produce a unit with about 10 or 12 shelves. Of course, the number of shelves will depend upon the size of the articles to be supported therein. In some instances, a greater number of shelves can be used in a unit vending packet when only small articles are to be handled. One skilled in the art can readily determine the number of shelves to be included in one unit by taking the size of the 10 article to be merchandised into consideration.

In Figs. 5 and 6, the improved vending packet is illustrated as being mounted in a vending cabinet. This cabinet may have any appropriate construction and it is herein shown as having a 20 rear wall 18, side walls 4 and a front wall 7 containing a glass window 8. Secured to the inner face of rear wall 18 is a holding member 13 which has turned edges at each side thereof to form grooves 17 capable of engaging the bands and the 25 edges of the vending packet. By the use of grooves 17 a unit vending packet can be slid or inserted within the vending cabinet. When the packet is mounted in groove 17, inturned edges 14 contact with bands 2 and form a frictional joint 30 therewith. This frictional joint maintains the vending packet in a given position in the vending cabinet. When it is desired to remove an article of merchandise 11 from the vending cabinet the lowermost edge of the vending packet 20 may be 35 grasped and drawn downwardly. As the motion progresses bands 2 are separated from each other and from the rear wall and assume a position somewhat like that shown in Fig. 6. When the bands and the upper and lower floors assume the 40 position illustrated in Fig. 6, article 11 slides from the shelf and may be caught in a receptacle or in the hand of the operator. The articles of merchandise 11, of course, may be regular or irregular in shape and may vary from candies to toys 45 or any other product to be filled or distributed.

In Fig. 3 I have illustrated a modified embodiment of the improved vending packet. This vending packet has rear walls 22 from which a plurality of shelves 24 project. Shelves 24 are 50 constituted of an upper and lower floor 25 and 25a respectively. As described hereinabove a triangular air space 1a is provided between the upper and lower floors.

Instead of using bands 2 to hold the vending 55 packet and shelves thereon in position, shoulders 26 are provided at the edge of the packet. These shoulders abut against each other and form a solid joint. If desired a strip of tape or the like can be glued to the edges so as to hold the adjacent walls in position with respect to each other. When the modified vending packet is to be inserted in the vending cabinet and the articles then placed on the shelves it is not necessary to use a tape because edges 14 in the vending cabinet will 60 press against the side edges of the vending packet and will hold the packet as a whole together.

In some instances the modified vending packet is placed in a box or carton which has a strip of cardboard or the like crimped over the side edges 70 of the vending packet or otherwise suitably affixed thereto. When this construction is used the carton has a similar construction to the vending cabinet shown in Figs. 5 and 6 except that cardboard walls are used in place of wood, metal, or the like.

The modified vending packet may be made from one piece of sheet material as indicated in Fig. 4. At each end of wall 22 a score or perforated line 15 is provided. This score line is set back from the outermost edge wall 2 so that a folding portion 5 shoulder 26 will be formed. At an intermediate portion of the strip of material between walls 22 a score line or perforation 21 is provided to divide the said strip into the upper and lower floors 25 and 25a of shelves 24. When this blank 10 is folded the upper and lower floors are joined at their outermost edges and are spaced apart at their innermost edges. This formation is due to the setting back of score line 15 from the outermost edges of walls 22 and by the provision of 15 shoulder 26.

Referring now more particularly to Fig. 7, a modified embodiment of my invention into a vending machine is illustrated. In this modified embodiment a cabinet 27 is provided having a discharge port 28, through which the articles to be dispensed are discharged. A partition wall 29 and a pair of guide rails 30 are arranged within the cabinet and co-operate with the marginal portions 32 of the vending packet to retain same in 20 the desired vertical position and at the same time permitting frictional displacement of the vending packet in the vertical and upward direction. The vending packet proper comprises the shelves 31 which are of a construction similar to 25 the shelves illustrated in Figs. 1 and 3 and are adapted to carry the articles to be dispensed (not shown). The upper and pulled out portion 33 of the vending packet is carried over the circumference of a small roller 34 and over the circumference of drive roller 35. Drive roller 35 is 30 provided with a series of pins 36 uniformly spaced around the circumference thereof, which are adapted to co-operate with correspondingly spaced perforations in the cardboard or the like 35 band forming the vending packet, so that the vending packet may be vertically displaced by the rotation of drive roller 35. The motive power for rotating the drive roller is supplied by means of a weight 38 suspended from a string or wire 37 40 which is wound around shaft 39 of the drive roller. Under the influence of weight 38, the drive roller 35 is rotated in clockwise direction 45 the uppermost vending shelf is drawn apart and the article on the shelf is dispensed and will slide down guard plate 40 to be discharged through discharge opening 28. Of course, suitable locking 50 means adapted to be actuated manually or automatically are preferably provided which normally prevent rotation of drive roller 35 and discharge 55 of the articles until a coin or otherwise controlled release mechanism is actuated. In view of the fact that such locking and releasing mechanisms are well known by those skilled in the art and do not form part of my invention no description 60 of these auxiliary devices will be necessary.

Although I have illustrated and described certain preferred embodiments of the invention, it is to be understood that variations and modifications may be made without departing from the 65 scope and spirit of the invention, as defined in the appended claims. For instance, the term vending packet and vending cabinet is intended to apply to any type of dispensing apparatus 70 whether manually or automatically operated or coin operated.

The present invention is a refile of my application bearing Ser. No. 504,706, filed on Dec. 26, 1930 and entitled Vending packets and the 75

method of making the same, abandoned June 28, 1933.

I claim:

1. A vending packet comprising a wall portion 5 of sheet material adapted to be mounted vertically in a vending cabinet, and a plurality of shelves of sheet material for supporting articles projecting transversely from said wall portion at spaced intervals and constituted of a top 10 floor and bottom floor which are joined together at the outermost free end and secured to the wall at the innermost end and separated by an appreciable air space, said wall portion and shelves being arranged in such a manner as to 15 be capable of being withdrawn from the cabinet.
2. A vending packet comprising a wall portion 20 of sheet material adapted to be mounted vertically and held at the sides thereof in a vending cabinet and a plurality of shelves of sheet material for supporting articles projecting transversely from said wall portion at substantially regularly spaced intervals, each of said shelves consisting of a top and a bottom floor having their outermost ends joined together and their 25 innermost ends joined to the wall portions in such a manner that the said shelves and wall portion can be withdrawn from a cabinet as a continuous strip, said top and bottom floors being separated by an appreciable air space.
3. A vending packet constituted of sheet material comprising a plurality of wall portions constituting the back of the packet and adapted to be mounted vertically in a vending cabinet, a plurality of side portions arranged laterally of the wall portions and adapted to cooperate with 30 each other to hold the wall portions in position, and a plurality of shelves projecting from said wall portions in a direction approximately transverse thereto and adapted to support articles, each of said shelves consisting of a top floor and a bottom floor joined to each other at their outermost edges and to the wall portions at their innermost edges in such a manner that the packet may be withdrawn from a vending cabinet as a continuous strip, said top and bottom floors being separated by an appreciable air space.
4. A vending packet constituted of sheet material comprising a plurality of wall portions having their tops and bottoms parallel to each other 40 and adapted to constitute the back of the packet and to be mounted in a vending cabinet, a plurality of bands located at each side of the packet and extending from the bottom of one wall portion to the top of the other, each of said bands being capable of being folded at an intermediate region thereof and being adapted to hold said wall portions in position, and a shelf interposed between adjacent wall portions and consisting of a top floor and a bottom floor joined together at 45 their outermost ends and joined at their innermost ends to the bottom of one wall portion and the top of an adjacent lower wall portion respectively whereby an article may be mounted on

each shelf and the packet may be withdrawn from a vending cabinet as a continuous strip, said top and bottom floors being separated by an appreciable air space.

5. An integral vending packet constituted of 5 cardboard comprising a plurality of rectangularly shaped wall portions spaced from each other and having their tops and bottoms parallel to each other, said wall portions being adapted to constitute the back of the packet and 10 to be mounted in a vending cabinet, a band located at each side of the packet and extending between and secured to adjacent wall portions, each band being adapted to fold at an intermediate region thereof and to hold the wall portions 15 in spaced position with respect to each other, said bands in their folded position occupying the side regions of the wall portions, and a shelf projecting in a direction substantially transverse to said wall portions and adapted to support 20 articles when mounted in a vending cabinet, said shelf consisting of a top floor and a bottom floor joined together at their outermost ends and joined to the bottom of a wall portion and to the top of an adjacent portion respectively and spaced from 25 each other to form a substantial triangularly-shaped air recess therebetween.

6. A vending packet blank of sheet material comprising a plurality of spaced wall portions having tops and bottoms parallel to each other, 30 means located at the sides of the packet to hold said wall portions in spaced relation with respect to each other, and a shelf interposed between adjacent wall portions and consisting of a top floor and a bottom floor joined together at 35 their outermost ends and to the bottom of a wall portion and the top of an adjacent one respectively, each shelf being secured to the wall portions in such a manner as to be capable of being folded in a direction substantially transverse to 40 said packet, and said top and bottom floors being separated by an appreciable air space.

7. An integral vending packet blank of cardboard comprising a plurality of regularly spaced wall portions having substantially rectangular 45 shapes and having their tops and bottoms parallel to each other, a narrow band located at each side of the packet and interposed between and secured to adjacent wall portions, a scored line at an intermediate region of said band to permit folding 50 thereof, and a shelf extending between adjacent wall portions and consisting of a top floor and a bottom floor joined together at their outermost ends and to the bottom of a wall portion and the top of an adjacent lower one, said top and bottom 55 floors being separated by an appreciable air space, the aforesaid elements being secured to and arranged with respect to each other in such a manner that each shelf projects in a direction substantially transverse to the wall portions and band 60 folds adjacent to the sides of the wall portions to hold them in position.

JAMES WELLFORD MARTIN.
